Inventor:

Jack Barofsky

UNITED STATES PATENT OFFICE

109,121

DESIGN FOR A FENDER FOR A MOTOR VEHICLE

Jack Barofsky, New York, N. Y.

Application November 20, 1937, Serial No. 73,056

Term of patent 14 years

To all whom it may concern:

Be it known that I, Jack Barofsky, a citizen of the United States, residing at 1451 Broadway, Room 603, in New York, county and State of New York, have invented a new, original, and ornamental Design for a Fender for a Motor Vehicle, of which the following is a specification, reference being had to the accompanying drawing, forming part thereof.

Figure 1 is a side perspective view showing my new design as it appears from the rear.

Figure 2 is a similar view as it appears from the front.

The side opposite that shown is open.

I claim:

The ornamental design for a fender for a motor vehicle, as shown and described.

JACK BAROFSKY.
